UNITED STATES PATENT OFFICE

93,403

DESIGN FOR A LIQUEUR DRINKING SET

Edward Kanter, Cleveland Heights, Ohio

Application December 1, 1933, Serial No. 49,907

Term of patent 7 years

To all whom it may concern:

Be it known that I, EDWARD KANTER, a citizen of the United States, residing at Cleveland Heights, in the county of Cuyahoga and State of Ohio, have invented a new, original, and ornamental Design for a Liqueur Drinking Set, of which the following is a specification, reference being had to the accompanying drawing, forming part thereof, wherein Fig. 1 is a perspective view; Fig. 2 is a side elevation, and Fig. 3 is a top plan view of a liqueur drinking set showing my new design. The circular elements disclosed on the side walls of the decanter or shaker indicate openings which are closed by an inner glass container so that the contents of the container are visible therethrough.

The shaker, tray and goblets are displayed, sold and used as a set.

The dominating feature of this design is the shaker and goblets which are complementary in shape, the upper portion of the shaker being similar to the lower portion of the goblets. The goblets and shaker can be placed upon the tray only in the position shown in the drawing.

I claim:—

The ornamental design for a liqueur drinking set substantially as shown and described.

EDWARD KANTER.
